UNITED STATES PATENT OFFICE.

FRANKLIN L. BARBER AND EDWIN W. WEBB, OF CHICAGO, ILLINOIS, ASSIGNEES TO
STANDARD CAR TRUCK COMPANY, OF CHICAGO, ILLINOIS, A CORPORATION OF
NEW JERSEY.

CAR-TRUCK.

1,351,459.

Specification of Letters Patent. Patented Aug. 31, 1920.

Application filed February 24, 1919. Serial No. 278,619.

To all whom it may concern:

Be it known that we, FRANKLIN L. BARBER and EDWIN W. WEBB, citizens of the United States, residing at Chicago, in the county of Cook and State of Illinois, have invented certain new and useful Improvements in Car-Trucks; and we do hereby declare the following to be a full, clear, and exact description of the invention, such as will enable others skilled in the art to which it appertains to make and use the same.

Our invention relates to improvements in car trucks, and particularly to six-wheeled equalized car trucks. To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a side elevation of the improved car truck with some parts illustrated by means of broken lines;

Fig. 2 is a longitudinal central section;

Fig. 3 is a fragmentary plan view of the improved car truck, as shown in Fig. 1;

Fig. 4 is a fragmentary detail view with some parts sectioned on the line 4-4 of Fig. 3;

Fig. 5 is a detail view in transverse section taken on the line 5-5 of Fig. 4;

Fig. 6 is a transverse section taken on the line 6-6 of Fig. 1; and

Fig. 7 is a transverse section taken on the line 7-7 of Fig. 1.

The truck frame, as shown, comprises hollow side members 8 and a pair of transoms 9 integrally formed with said side members. The transoms 9 are channel-shaped in cross section and horizontal outturned flanges 10 are integrally formed with the upper edges of the sides thereof to reinforce the same.

By reference to Figs. 6 and 7, it will be noted that the transoms 9 are downwardly curved to give the same a considerable drop. It will also be noted, by reference to Fig. 2, that the inner walls of the transoms 9 are considerably lower than the outer walls to afford clearance for a casting that connects the members of a double bolster, as will presently appear. Openings are provided in the bottom of the transoms for the escape of rain, snow, ice and dirt.

Pairs of pedestals 11 have their upper ends detachably secured to the bottoms of the side members 8 by short nut-equipped bolts 12. Between the members of each pair of pedestals 11, the side members 8 are provided with notches or arches 13, which afford clearance for journal boxes, as will presently appear. On the inner face of each pedestal 11, is a pair of transversely spaced guides 14, the upper ends of which project above the pedestals and into the arches 13, as best shown in Fig. 6. Tie bars 15 connect the members of each pair of pedestals 11 and are detachably secured thereto by nut-equipped bolts 16. The journal boxes, wheels and axles of the improved car truck are indicated by the numerals 17, 18 and 19, respectively. The journal boxes 17 are mounted between the guides 14, with freedom for vertical movement, and cast on the tops thereof are ribs or lugs 20 that are segmental in cross section.

Within each side member 8, is a pair of longitudinally aligned equalizer bars 21, the outer ends of which rest on the tops of the two end journal boxes 17 and their inner ends, which abut, rest on the tops of the intermediate journal boxes 17. In the outer ends of the equalizer bars 21, are segmental seats 22 which receive the respective ribs 20, and correspondingly formed half seats 23 are formed in the inner ends of said equalizer bars, which receive the lugs 20 on the intermediate journal boxes.

Suspended from each equalizer bar 21, is a hanger, in the form of a bolt 24, having an eye 25 in its upper end and a T-head 26 on its lower end. These hanger bolts 26 support spring bases 27 that underlie spring caps 28 integrally formed with the bottoms of the side members 8. Compressed between each spring base 27 and the overlying spring cap 28, are four coiled springs 29. The upper ends of the hanger bolts 24 extend into sockets 30 formed in the bottoms of the equalizer bars 21 and are pivotally connected to said bars by pins 31 mounted in aligned bores in the equalizer bars 21 and the eyes 25 in the hanger bolts 24. The sockets 30 hold the hanger bolts 24 against lateral movement, but permit the required swinging movement thereof longitudinally of the car truck. These hanger bolts 24 extend through longitudinally elongated slots 32 formed in the spring caps 28 and elong-

gated slots 33 in the spring bases 27, which permit the insertion of the T-heads therethrough. On the bottoms of the spring bases 27, are concave seats 34, which fit onto 5 the convex upper faces of the T-heads 26 and extend at right angles to the slots 32. To apply the spring base 27 to the hanger bolts 24, the same are first given an upward movement to carry the T-heads 26 through 10 the slots 33 and then given a one-quarter turn to carry the seats 34 onto said T-heads. With the springs 29 compressed between the spring bases 27 and spring caps 28, said spring bases are securely held, by the interlocking engagement of their seats 34 with the T-heads 26, against turning movement 15 with respect to the hanger bolts 24.

The members of a double bolster 35 are mounted, one in each of the channel transoms 9, and are rigidly connected by a heavy H-shaped casting 36 that is bolted thereto and has formed therewith the lower members of a center bearing 37. The members of the double bolster 35 are supported on lateral motion bearing devices, each of 20 which, as shown, comprises three rollers 38 mounted in seats formed in a roller bearing plate or base 39. These roller bearing bases rest on the bottoms of the transoms 25 9 close to the side members 8 and may be secured against lateral movement by any suitable means. Contours 40 are formed in the under faces of the members of the bolster 25 to receive said rollers 38. By reference 30 to Fig. 7, it will be noted that the ends of the bolster 35 terminate short of the inner walls of the side members 8, in the normal position thereof, and which walls afford stops to limit the lateral movement of said 35 bolster.

To hold the members of the bolster 35 within the transoms 9, nut-equipped bolts 41 are extended through alined bores in the side walls of said transoms and which bolts 45 are located slightly above the upper faces of the members of the bolster to permit the required vertical movement thereof, due to the action of the lateral motion bearing devices. Brake hanger lugs 42 are cast with 50 the vertical walls to the transoms 9, just under their flanges 10, and lower side bearing plates 43 are secured to the H-frame 36. To facilitate the casting of the side frames 8 and the assembling of the equalizer bars 55 21, openings are formed in the ends and walls thereof. By reference to Fig. 2, it will be noted that the dropped inner flanges 10 of the transoms 9 afford sufficient clearance to permit the required vertical movement 60 of the bolster 35. Normally, the pivot pins 31 are held against endwise displacement by the vertical walls of the side members 8. To permit the application of the pivot pins 31 to the equalizer bars 21 and 65 the removal of the same therefrom, annular

openings 45 are formed in the outer vertical walls of the side members 8. These openings 20 are normally out of alinement with the pivot pins 31, and to permit said pins to be inserted or removed therethrough, it is 70 necessary to lift the side frames 8 with respect to the journal boxes 17.

From the above description, it is evident that the load of the car is directly on the double bolster and it, in turn, is supported 75 from the truck frame by lateral motion bearing devices. The truck frame and load carried thereby are applied to the journal boxes through the coiled springs and equalizer bars. This construction, of course, 80 allows the wheels to move vertically and independently of each other.

What we claim is:—

1. In a car truck, the combination with a frame having side members and a pair of 85 transoms rigidly connecting said side members, of a double bolster, lateral motion devices carried by the transoms and supporting the double bolster with freedom for lateral movement entirely between the frame 90 side members, and stops for limiting the lateral movement of the double bolster.

2. In a car truck, the combination with a frame having side members and a pair of channel transoms rigidly connecting said 95 side members, of a double bolster, the members of which are connected and mounted in said transoms with freedom for lateral movement entirely between said side members, and lateral motion devices interposed 100 between the bottoms of the transoms and the members of the bolster, and stops for limiting the lateral movement of the double bolster.

3. In a car truck, the combination with a 105 frame having side members and a pair of channel transoms cast therewith, of a double bolster, the members of which are connected and mounted in said transoms with freedom for lateral movement between 110 said side members, and lateral motion devices interposed between the bottoms of the transoms and the members of the bolster.

4. In a car truck, the combination with a frame having side members and a pair of channel transoms cast therewith, of a double 115 bolster, the members of which are connected and mounted in said transoms with freedom for lateral movement between said side members, said side members acting as stops 120 to limit the lateral movement of the double bolster, and lateral motion devices interposed between the bottoms of the transoms and the members of the bolster.

5. In a six-wheeled car truck, the combination with a frame having hollow side members, of journal boxes, pairs of equalizer bars having their outer ends fulcrumed on the end journal boxes and their inner ends fulcrumed on the intermediate journal 130

- boxes, hanger bolts having their upper ends mounted in cavities in the under sides of the equalizer bars and provided with eyes, pins mounted in the equalizer bars and extending through the eyes in the hanger bolts, the vertical walls of said side members normally preventing endwise displacement of the pins and having apertures through which the pins may be inserted, 5 said apertures being normally out of alignment with said pins, spring bases on the lower ends of the hanger bolts, and springs compressed between the spring bases and spring caps.
- 10 6. In a car truck, the combination with a frame, of journal boxes, equalizer bars carried by the journal boxes, hanger bolts suspended from the equalizer bars and having integral T-heads on their lower ends, spring bases having apertures through which said 15 heads may be inserted by a compound axial

and turning movement, said spring bases also having seats arranged to interlock with said head to hold the spring bases thereon, and springs compressed between the spring bases and frame. 25

7. In a car truck, the combination with a frame, of pairs of pedestals detachably secured to said frame, said frame between the members of each pair of pedestals being arched thereabove, guides on the inner faces of the pedestals extending thereabove and into said arches, and journal boxes mounted between said guides for vertical movement. 30
